Primary Examiner—Holly Baynham*Attorney, Agent, or Firm*—Stetina Brunda Garred & Brucker[57] **CLAIM**

The ornamental design for a floating floor installation fixture, as shown and described.

DESCRIPTION

FIG. 1 is a perspective view depicting a floating floor installation fixture of the present invention showing my new design with the phantom lines, including those in the left portion showing a fixture of the present invention and a spacer there behind, depicting solely environmental structure and forming no part of the claim design;

FIG. 2 is a front perspective view thereof;

FIG. 3 is a front elevational view thereof; and,

FIG. 4 is a side elevational view thereof with the phantom lines depicting solely environmental structure and forming no part of the claim design.
